HYPODERMIC INJECTION APPARATUS, AND
METHOD OF PREPARING FOR AND MAK-
ING SUCH INJECTIONSCloyd C. Dickinson and Clayton F. B. Stowell,
Chicago, Ill., assignors, by direct and mesne as-
signments, to Frank C. McCrum, Chicago, Ill.

Application April 21, 1933, Serial No. 667,236

5 Claims. (Cl. 128—216)

Our invention relates to means for effecting convenient and sterile hypodermic injections, and to accomplish the desired result we utilize the well known and commonly used syringe constructed to utilize cartridge containers for the liquid to be injected.

It is well known that certain chemicals commonly used as anesthetics tend to deteriorate rapidly when in solution, and an object of our invention is to provide means whereby the medicament, such as novocaine may be isolated from the carrier or diluent until actually ready for use.

A further object is to provide suitable means for accomplishing this result and so arranging the parts that it will be impossible for a user to make an error in the act of loading and operating the syringe.

The invention will be more readily understood by reference to the accompanying drawing, in which:

Fig. 1 is a side elevation of a conventional syringe into which the cartridge of our invention has been loaded, the view showing the syringe partly emptied by action of the plunger on the plug closure for the cartridge;

Fig. 2 is a view somewhat enlarged of the cartridge of our invention;

Fig. 3 is an enlarged sectional view of one end of the cartridge;

Fig. 4 is a sectional view of the assembly of the cartridge and syringe at the lower end showing the action following the placing of the cartridge in position, and

Fig. 5 is a composite perspective view of the plug, sleeve and closure for the lower end of the cartridge.

In the drawing in Fig. 1 we have shown a conventional form of syringe in which the upper end is adapted to be swung out of line with the cylindrical body portion or barrel 11 in order to present an open end of the barrel for reception of the cartridge. The cartridge consists of a tube 6, preferably composed of glass, and of uniform diameter from end to end. The lower or left hand end as viewed in Fig. 2 is closed by means of a plug 1 having a flange 2 that serves to limit the entrance of the plug into the tube. The plug has a chamber or recess 3 axially arranged therein and within this chamber we have shown a small cylinder 8 normally open at both ends and used merely to stiffen the walls of the plug or stopper. Of course, it is obvious that the cylinder 8 may be omitted if desired, the chamber

within the plug constituting the container for the drug. In the drawing we have shown the outer end of the cylindrical member 8 as closed by a disc 4 which will preferably be of a material that will not be readily punctured by the inwardly projecting end of the hypodermic needle. The disc will be sealed in place by suitable means. A carrier or diluent for the medicament is contained within the closed tube, as indicated at 7, the medicament within the chamber in the plug being indicated at 10.

At its opposite end the cartridge is closed by means of an unflanged plug 12 that acts as a piston when displaced by the thrust of the plunger 13 of the syringe.

It being understood that the hypodermic needle 14 is firmly held in the position shown in the drawing with its inner end 15 projecting into the space within the syringe cylinder or barrel. To load the syringe, the upper end is swung to open the barrel, whereupon the cartridge is placed in the barrel and pushed downward. As a result of this manipulation, the inwardly projecting end 15 of the needle is forced through the non-metallic plug 1, thence through the chamber 3 and into contact with the hard disc 4, breaking the seal and displacing the disc, as best shown in Fig. 4. Inasmuch as the opening in the chamber that is closed by the disc 4 is the full size of the chamber and as the closure will be entirely removed from the adjacent space, the two materials—that is the medicament 10 and the carrier 7—will immediately enter into a mixture. Thereafter the upper end of the syringe is swung into closed position; and it will be noted that it cannot be swung into that position unless the cartridge is pushed all the way in; in other words, the syringe cannot be closed until the cartridge is placed in such position that the mixture of the two materials has already taken place. After the syringe is closed the plunger 13 may be forced against the unflanged plug 12 in the tube 6 and the mixture of the medicament and diluent is forced outwardly through the hypodermic needle.

The particular advantage in the construction shown and described is that of certainty of freshness of the mixture, complete sterility of the syringe and certainty of combination or mixture of the two chemicals before any discharge from the cartridge can be effected.

Obviously the construction is capable of some modifications and we do not wish to be limited except as indicated in the appended claims.

We claim:

1. In combination, a syringe having a plunger, a cylindrical body and a hollow needle with its inner end projecting into the space within the body and its outer end projecting beyond the body, and a discardable cartridge adapted to be received within said body and when so received to constitute the cylinder and piston of the syringe, said cartridge consisting of a tube adapted to contain a solvent or carrier for a medicament, a flanged, non-metallic plug adapted to close one end of the tube and provided with an axial chamber open to the inside of the tube and adapted to contain said medicament, a closure sealed in the open side of said chamber, said closure being in position to be displaced by the inwardly projecting end of the needle as a necessary result of the act of loading the cartridge into the syringe body and thereby to combine the medicament and carrier, the opposite end of the tube being closed by an unflanged plug adapted to be displaced by the inward movement of the plunger and thereby to act as a piston for ejecting the mixture within the tube through the needle.

2. A hypodermic injection device, comprising in combination, a syringe having a plunger, a barrel and a hypodermic needle, the parts being adapted to be operated to present an open upper end of the barrel, said needle being positioned with its inner end projecting into the barrel and its outer end projecting beyond the barrel, and a cartridge adapted to be received within the open end of the barrel and when so received to constitute the cylinder and piston of the syringe, said cartridge consisting of a tube of substantially uniform diameter from end to end and adapted to contain a carrier for diluent or a medicament, a flanged non-metallic plug adapted to close one end of the tube and provided with a chamber one side of which is open to the inside of the tube, said chamber being adapted to contain said medicament, a closure sealed in the open side of said chamber, said closure being adapted to be displaced by the inwardly projecting end of the needle as a result of the placing of the cartridge in operative position in the barrel of the syringe whereby said chamber is opened and the medicament is permitted to intermix with the diluent, the opposite end of the tube being closed by an unflanged plug adapted to be displaced by the plunger and thereby to act as a piston for ejecting the mixture within the tube through the needle.

3. A cartridge for use in hypodermic syringes, consisting of a tube of substantially uniform diameter from end to end, a flanged plug composed of rubber or similar material for closing

one end of the tube, said plug having a chamber therein with an open side, said opening being of substantially the cross sectional area of the chamber, a disc adapted to be sealed in position to close said opening and when displaced by a needle projected through the rubber outer wall of the plug to permit a rapid discharge of the contents of the chamber into the tube, and an unflanged plug on the opposite end of the tube, said plug being adapted to act as a piston to effect the discharge of the contents of the tube through the outlet provided by the said needle.

4. The combination with a syringe including a cylindrical body, a plunger, and a hollow needle having its inner end projecting into the space within the body and its outer end projecting beyond the body, of a discardable cartridge adapted to be received within said body and when so received to constitute the cylinder and piston of the syringe, said cartridge comprising a tube adapted to contain a solvent or carrier for a medicament, a non-metallic plug adapted to close one end of the tube and provided with an axial chamber open to the inside of the tube and adapted to contain said medicament, a disc overlying the inner face of the non-metallic plug and sealed thereto over a relatively small area for closing the axial chamber but adapted to be readily displaced therefrom by engagement of the inwardly projecting end of the needle as a necessary result of the act of loading the cartridge into the syringe body and thereby to combine the medicament and carrier or solvent, the opposite end of the tube being closed by a plug adapted to be displaced by inward movement of the plunger and thereby to act as a piston for ejecting the mixture within the tube through the needle.

5. A hypodermic syringe comprising a barrel having a hypodermic needle mounted at one end and extending into the barrel, a plunger mounted at the other end, a discardable cartridge adapted to be received in said barrel through said plunger end, said cartridge comprising a tube having an imperforate plug at one end adapted to be pierced by said needle and a piston plug at the other end adapted to be operated by said plunger, said plugs defining a chamber adapted to hold liquid, said imperforate plug having an axial chamber open to the first chamber and adapted to contain medicament, a closure sealing the open end of said axial chamber and adapted to be displaced by the inwardly extending end of the needle as a necessary act of seating the cartridge in the barrel, thereby to combine the medicament and liquid.

CERTIFICATE OF CORRECTION.

Patent No. 2,238,582.

April 15, 1941.

CLOYD C. DICKINSON, ET AL.

It is hereby certified that the above numbered patent was erroneously issued to Cloyd C. Dickinson and Clayton F. B. Stowell, as assignors, by direct and mesne assignments, to Frank C. McCrum, whereas said patent should have been issued to Cloyd C. Dickinson and Clayton F. B. Stowell, said Stowell assignor by mesne assignments of his entire right to Frank C. McCrum, of Chicago, Illinois, as shown by the record of assignments in this office; and that the said Letters Patent should be read with this correction therein that the same may conform to the record of the case in the Patent Office.

Signed and sealed this 1st day of July, A. D. 1941.

(Seal)

Henry Van Arsdale,
Acting Commissioner of Patents.
